CONCRETE PILING WALL UNIT

Andrew Hood, Llanwrda, Wales

Application February 15, 1945, Serial No. 578,055
In Great Britain February 10, 1944

9 Claims. (Cl. 61—59)

This invention is for improvements in or relating to concrete piling wall units and has for an object to improve the alignment of the piles during driving operations with a view to ensuring that in the driven state the alignment of the piles is correct.

In my prior British patent specification No. 342,240 I have described concrete piling wall units having longitudinal tongues formed on the driving and driven faces.

The term "driving face" indicates that face of the unit being driven which is adjacent to the "driven face" of the unit already in position. This term "driven face" means the free (i. e. disengaged) face of the unit last driven.

The piling wall units of my prior construction are provided with tongues on the driving and driven faces which tongues extend over substantially the whole length of the driving and driven faces of the piling wall unit there being interruptions for the relief of material trapped between the end of the tongue on the driving face and the tongue on the driven face. The relief or escape of the material takes place through these interruptions and the interruptions are staggered on the driving and driven faces so that when the piling wall units are driven into their proper relative positions the interruptions in the tongue on the driven face will be obscured by the remaining portion of the tongue on the driving face and vice versa.

In that prior specification, I described the formation of a cavity between the adjacent driven and driving faces of a pair of piling wall units formed by means of a rebate formed in the upper part of one of the tongues; into this cavity there was poured mortar to form a positive seal between the units so as to prevent percolation of water, silt or the like from the front to the back of the assembled piling wall units or vice versa.

According to the present invention, there is provided a concrete piling wall unit having a driving and a driven face, a tongue formed on the driving face extending along substantially the whole length of said driving face, a rebated tongue formed on the driven face in a position complementary to said first tongue and extending along substantially the whole length of said driven face with the rebate thereon terminating short of the end of said tongue, said tongue and said rebated tongue being so disposed that a cavity for sealing material is formed between the driven and driving faces of adjacent wall units, and a guide member secured to the driven face of said wall unit to lie within said rebate to

engage with the tongue and driving face of an adjacent wall unit or with a guide member positioned therein.

According to one feature of the invention, the 5 guide member comprises a pipe of such a size as to engage with all four walls of the rebate which define the cavity whereby the wall unit being driven is guided in its proper relationship with the wall unit last driven; the pipe may be either round or square in cross-section.

The pipe is secured in position, before the wall unit is slung for driving, by means of a strapping member at the top of the wall unit and by engagement with a projection formed on or secured to the wall unit in an appropriate position 15 near to the bottom of the rebate. When the wall unit has been driven into position the pipe is charged with mortar and gradually withdrawn from the cavity as the mortar is extruded from its end to fill up the cavity and thereby to form 20 a seal between the pair of adjacent wall units which may extend for the full length of the cavity. The pipe can, of course, be used again.

According to another feature of the invention 25 the driving and driven faces of the unit each have attached thereto or secured therein a U-shaped metal interlocking member, constituting said guide member, extending along a part of the length thereof, so located as to lie in the 30 cavity formed between pairs of adjacent units, the cavity being formed by a rebate in the longitudinal tongue on the driven face extending from the top end.

The advantage of the above-described construction lies in that the tongue on the driving face will engage with the side of the U-shaped metal interlocking member on the driven face and consequently throughout the whole of the driving operation the unit being driven will be 40 guided. The interlocking of the two U-shaped metal interlocking members ensures that the units are positively retained in their correct relative positions throughout the whole of the driving operation.

The U-shaped metal interlocking members can either be continuous or they can be discontinuous but in the case where discontinuous interlocking members are utilised the discontinuity must be such that there is a positive interlock throughout the whole of the driving operation from the time that the interlocking first takes place.

The following is a description of various embodiments of the invention described in relation 55 to the accompanying drawings in which:

Figure 1 shows a side elevation of the driven side of a concrete wall piling unit.

Figure 2 shows the driving side of a concrete wall piling unit.

Figure 3 is a sectional plan showing the engagement between adjacent concrete piling wall units.

Figure 4 shows a round cross section pipe acting as guide member.

Figure 5 shows a square cross section pipe.

Figure 6 shows one method of securing the grout pipe near the foot of the wall unit.

Figure 7 shows one method of securing the pipe at the head of the wall unit.

Figure 8 shows the arrangement of a jetting pipe.

Figure 9 illustrates the use of interlocking grip members.

Figure 10 is a modification of the arrangement of Figure 9 and

Figure 11 shows a further modification of interlocking grip units in conjunction with a pipe.

The concrete piling wall unit illustrated in side elevation in Figures 1 and 2 shows respectively the driven and driving faces of a wall unit, the wall unit being indicated generally by the reference numeral 1.

The driving face has a tongue 2 extending over substantially the whole of its length and extending approximately across half the width of the driving face. On the driven face the tongue 3 extends over substantially the whole length of the driven face in a similar manner to the tongue 2 but is formed with a rebate 4 the arrangement being such that when two wall units are in position they form a cavity in the manner shown in Figure 3 and indicated by the reference numeral 11 showing the cavity filled with a sealing material such as cement grout or mortar.

Disposed within the rebate 4 is a grout pipe, indicated in Figures 4 and 5 by the reference characters 8 and 12, indicating respectively round cross section and square cross section pipes.

In order to locate the lowermost end of the pipe a peg or the like indicated at 6 in Figure 6 is secured in the bottom end of the tongue 3 to extend up into the rebate 4 and this peg may be secured in the wall unit by a fish-tail portion bedded in the wall unit as shown at 7.

The upper end of the pipe may be located in position by means of a metal grip member indicated at 9 in Figure 7. The grip member 9 surrounds the driving head 10 and the driving dolly is indicated in dotted lines surrounding the driving head 10.

It will be appreciated that, during driving of a concrete piling wall unit in a position adjacent the wall unit already driven to the desired depth and in the desired position, the driving face of the next wall unit is suspended in a position such that the side face of the tongue 2 abuts against the driven face of the last wall unit and the pipe 8 or 12 located in the rebate 4 in the tongue 3 on the driven pile engages against the driving face of the driving pile. By this means the driving pile is being guided throughout the whole of the driving operation in its proper relationship with respect to the driven pile and to facilitate this the lowermost end 15 of the driving pile is champed to assist in keeping the foot of the driving pile in close engagement with the driven face of the driven pile whilst the foot 16 of the unit is similarly cut away so as to further assist the pressure of the foot of the unit against the already driven unit; the position of the parts 15

and 16 is well illustrated in Figure 8 in which there is also shown a modified fixture for the lowermost end of the pipe 8. In this modification instead of using a peg 6 a pipe 13 is arranged to project up into the rebate 4, the pipe communicating through the body of the foot of the wall unit to emerge on the driven face thereof at 14 to facilitate jetting during the driving of the driving pile as is commonly done. The projecting pipe 13 may be formed with a screw-thread for engagement with a corresponding screw-thread on the pipe 8 of Figure 4 so that, during driving of the wall unit, the pipe 8 may be screwed on to the pipe 13 so that jetting may be effected whilst at the conclusion of driving the pipe 8 is unscrewed from the pipe 13 and is used for conveying grout into the cavity formed by the rebate 4 so as to form the seal 11 shown in Figure 3.

A modification of the arrangement described with relation to the foregoing figure is illustrated in Figure 9 in which, instead of locating a pipe such as 8 or 12 within the rebate, an interlocking member 17 is secured within the rebate 4 having an end 19 which is arranged so as to engage within the space formed in the U of a cooperating interlocking member 18 secured in the driving side of the driving unit and having its U end 20 arranged to engage in the U formed by the member 17. It will be appreciated that the driving pile is lowered into position so that the member 18 is so placed that the end 20 thereof interlocks with the member 17 and its end 19 to provide a positive interlock whereby the driving pile is positively guided throughout the whole of the driving operation.

The interlocking members 17 and 18 may be formed of the usual wedge grip shape in section (as shown in Figure 9) or alternatively they may be formed from standard sections such as bulb angles with equal or unequal angles or they may even consist simply of bent plate, for example, of a thickness of about a $\frac{1}{4}$ ".

The interlocking members 17, 18 may be permanently secured in the driving and driven faces 45 respectively of the piling wall unit, for example, by means of fish-tailed projections (as shown) being placed in position when the unit is being cast. With the interlocking members so secured in the unit they form a permanent interlock between adjacent piling wall units in the finished structure.

By reason of the U-shape of the interlocking members a labyrinthine passage is formed in the cavity between adjacent units and this labyrinthine passage may form a sufficient seal against the passage of water or silt between the joints or in any event is very rapidly blocked by the ingress of small particles e. g. silt.

An alternative method of securing the interlocking members to the faces of the piling wall unit is shown in Figure 10 and consists in casting the said units with dove-tailed longitudinal recesses 29 and 30 and in securing the metal interlocking members 31 and 32 to the unit by means of cooperatively shaped members 21 and 22 formed preferably of wood, to which the metal interlocking members are secured either by bolts or screws 23 and 24 or in any other convenient manner; the dove-tailed recesses 29 and 30 and cooperating members 31 and 32 are preferably slightly tapered and are forced into position before the unit is to be driven into its final position so that the interlocking members can fulfil their function of guiding and locking adjacent units together 70 during the driving operation. When the driving

operation is completed the interlocked two interlocking members 31, 32 can then be removed, together with the cooperating members 21 and 22 in which they are secured leaving a cavity between the adjacent driving and driven faces which cavity is dove-tailed at its ends; by filling this cavity with mortar or the like a very strong permanent impervious and indestructible joint is formed between the units. It will be appreciated of course that if preferred the dove-tailed members 21, 22 carrying the interlocking members 31, 32 can be left in position in which case they will themselves effect a seal as described above although it will also be appreciated that if desired, or if thought necessary, the space left around the interlocked U-shaped members may be filled with a sealing composition, for example, a grout might be poured down so as to block the labyrinthine passage above referred to.

A further modification is illustrated in Figure 11 where a number of anchor units 25 are fixed respectively along the inner edge of the rebate 4 of the tongue 3 and in the angle formed between the driving face of the unit and the tongue 2. An interlocking member 26 having a shaped end 27 arranged to slide within the hook-like part 28 of the anchor member 25 is inserted in position both in the rebate and in the angle between the tongue 2 and the driving face of the wall unit, whilst at the same time within the rebate there is located a pipe 8 corresponding with that shown in Figure 4 screwed on to the end of the pipe 13 corresponding to that shown in Figure 8.

The shape of the interlocking member 26 is such that the two cooperating interlocking members 26 mutually embrace the pipe 8 and thereby become locked together. The arrangement is such that the interlocking member 26 may, when the piles have been driven, be withdrawn from engagement with the hook 28 of the anchor member 25 while the pipe 8 may be unscrewed from the pipe 13 and withdrawn either prior to or during the grouting operation.

Thus in the modification shown in Figure 11 the interlocking member and grouting pipes are recoverable.

The constructions just described not only have the advantage that the driving face is positively guided and held throughout the whole of the driving operation but also by reason of the rebate being formed in the tongue on a driven face of a piling wall unit uniformity of depth of driving of the several units, in the formation of a wall, can be achieved by reason of the engagement of the metal interlocking member on the driving face of a unit with the bottom face of the rebate in the longitudinal tongue in the driven face of the adjacent unit.

In my prior British patent specification No. 324,240 I have described the tongues of driving and driven faces as being inclined at an angle to the direction of the driving of the unit; I have found that this is possibly slightly disadvantageous as I have found that with the tongues so formed there was some tendency for rotation of the unit to occur during driving; therefore it is preferred now to give the bottom-most end of the projection on the driven side of a unit a slight champfering or a 45° angle drift in the line of driving. This champfer or drift assists in keeping the foot of a unit closely driven up against the driven face of the adjacent unit during the driving and this action is further enhanced by the usual arrangement of the foot of the unit also with a champfer on the driven side. Such

champfers or drifts have already been described in relation to Figure 8 of the drawings but are not to be regarded as forming an essential feature of my construction.

5 The tongue 2 may be interrupted as in my prior British patent specification to relieve material trapped during driving whilst the tongue 3 may also, if desired, be similarly interrupted below the rebate 4; the interruptions should not coincide with one another in the finally driven positions of the wall units.

What I claim is:

1. A concrete piling wall unit having a driving and a driven face, a tongue formed on the driving face extending along substantially the whole length of said driving face, a rebated tongue formed on the driven face in a position complementary to said first tongue and extending along substantially the whole length of said driven face with the rebate thereon terminating short of the end of said tongue, said tongue and said rebated tongue being so disposed that a cavity for sealing material is formed between the driven and driving faces of adjacent wall units, a guide member 15 secured to said driven face so as to lie wholly within said rebate and to extend along substantially the whole length thereof said guide member being formed with an end portion of arcuate cross-section, a grouting pipe located within said rebate in engagement with said arcuate portion of said guide member and a second guide member, of the same shape and of substantially the same length as the first said guide member, secured to the driving face adjacent the tongue thereon 20 in such a position that it will cooperate during and after driving with the guide member and pipe on the driven face of a wall unit already driven into position to form a positive guide and interlock for the wall unit being driven.

2. A concrete piling wall unit having a driving and a driven face, a tongue formed on the driving face extending along substantially the whole length of said driving face, a rebated tongue formed on the driven face in a position complementary to said first tongue and extending along

45 substantially the whole length of said driven face with the rebate thereon terminating short of the end of said tongue, said tongue and said rebated tongue being so disposed that a cavity for sealing material is formed between the driven and driving faces of adjacent wall units, a grouting pipe 30 releasably engaged with locating means disposed within the rebate adjacent the lower end thereof, a guide member secured to said driven face so as to lie wholly within said rebate and to extend along substantially the whole length thereof said guide member being shaped to engage with and partly embrace said grouting pipe and a second guide member, of the same shape and of substantially the same length as the first said guide member, secured to the driving face adjacent the tongue thereon in such a position that it will cooperate during and after driving with the guide member and pipe on the driven face of a wall unit already driven into position to form a positive guide and interlock for the wall unit being driven.

3. A concrete piling wall unit according to claim 2 wherein said locating means for the grouting pipe is a jetting pipe communicating with the foot of the wall unit and is adapted to convey jetting fluid introduced into the grouting pipe to the foot of the wall unit during driving thereof.

4. A concrete piling wall unit having a driving 70 and a driven face, a tongue formed on the driving

face extending along substantially the whole length of said driving face, a rebated tongue formed on the driven face in a position complementary to said first tongue and extending along substantially the whole length of said driven face with the rebate thereon terminating short of the end of said tongue, said tongue and said rebated tongue being so disposed that a cavity for sealing material is formed between the driven and driving faces of adjacent wall units, a guide member secured to said driven face so as to lie wholly within said rebate and to extend along substantially the whole length thereof, said guide member being formed with its edge formed with a hook-like cross section, a secondary guide member disposed within said rebate in locking engagement with the hook-like edge of said guide member and a second guide member, of the same shape and of substantially the same length as the first said guide member, secured to the driving face adjacent the tongue thereon in such a position that it will cooperate during and after driving with the guide member and secondary guide member on the driven face of a wall unit already driven into position to form a positive guide and interlock for the wall unit being driven.

5. A concrete piling wall unit according to claim

4 wherein said secondary guide member is positively located at its lower end upon the lower end surface of said rebate.

6. A concrete piling wall unit according to claim 4 wherein the two said guide members and the secondary guide member are releasably secured to said wall unit to be recoverable therefrom.

7. A concrete piling wall unit according to claim 2 wherein said guide members are detachably secured to the driving and driven faces of said wall unit.

8. A concrete piling wall unit according to claim 2 wherein a plurality of guide-member-retaining means are permanently secured in the driving and driven faces of said wall unit and are arranged for sliding engagement with said guide members.

9. A concrete piling wall unit according to claim 2 wherein said wall unit is formed with a dove-tailed longitudinal recess extending along at least a part of the length of each of the driving and driven faces thereof and wherein the guide members are each secured to dove-tailed supporting members adapted to be slidably engageable with said dove-tailed recesses.

ANDREW HOOD.
